UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,238,160.

Specification of Letters Patent. Patented Aug. 28, 1917.

Application filed August 26, 1916. Serial No. 116,993.

To all whom it may concern:

Be it known that I, ALBEN E. LUNDELL, a citizen of the United States, residing at New York, in the county of Bronx and State 5 of New York, have invented certain new and useful Improvements in Telephone Systems, of which the following is a full, clear, concise, and exact description.

The present invention relates generally

10 to telephone systems of the semi-automatic or semi-mechanical class in which operators use manual equipment in establishing portions of the connections between telephone lines, and automatic switch mechanism is 15 employed in establishing other portions of such connections or in bringing the operators into communication with the subscribers or each other.

More particularly, the invention has to 20 do with systems in which the automatic switch mechanisms place an operator, sometimes called a "tandem" operator, into communication with an operator at a distant exchange and in which the designation of 25 the called line is automatically indicated to the "tandem" operator and then read off by her to the distant operator.

The principal object of the invention is 30 to simplify the work of the operators. In so doing the number of indications to be read off by the tandem operator is reduced, as compared with prior art systems, and the required manual operations of the terminating operator are lessened. In prior systems 35 of the art, upon which the present invention is an improvement, an arrangement of circuits and keys was employed by which the tandem operator could connect to a number of terminating operators' equipments. By the present invention these keys 40 and their circuits are done away with. Furthermore, with these prior art systems it was necessary to employ annunciators to indicate more designations than is required 45 by the present invention. In the present case the automatic switch mechanisms perform certain of the functions which were formerly performed by the operators. The 50 automatic switches now pick out the trunks instead of the terminating operator doing so, as was the case in the prior art systems and they perform the functions formerly 55 performed by the keys.

The various aspects and features of my invention will be more fully understood by

reference to the following detailed description taken in connection with the accompanying drawing and the scope of the invention will be more particularly pointed out in the appended claims.

In said drawings I have illustrated the present invention by a diagram in six figures placed together in the manner indicated in Figure 1^a.

In the system herein disclosed, which is 65 merely typical, three operators are required to establish a connection between subscribers' lines. The first, or initiating operator, answers the call of the subscriber and by a suitable sender causes the calling line circuit to be extended to a tandem operator. At the same time an indication corresponding to the called line is displayed before the tandem operator and her telephone set is 70 automatically connected to an automatically selected order wire or trunk running to a terminating operator's equipment at the desired distant exchange. The terminating operator, when brought into communication with the tandem operator, designates a 75 trunk to which the tandem operator connects the extended calling line circuit. At this time the tandem operator reads off the 80 displayed indication to the terminating operator and the latter completes the connection to the called line. As soon as the tandem operator connects the calling line circuit to the designated trunk, the automatic switching mechanism employed in bringing the tandem operator's equipment into circuit with the initiating operator's sender, 85 in displaying the called line designation and in connecting the tandem operator's head-set into circuit with that of the required distant operator, is freed for further 90 use in establishing other connecting circuits between calling and called lines. At the conclusion of conversation between the parties, the apparatus which has been engaged in maintaining the conversational circuit, 95 is restored to normal by the three operators taking down the connections in response to suitable supervisory indications.

Entering upon the description of the diagram somewhat more in detail, it will be 105 seen that the subscriber's equipment at substation M is connected by line L to a central office or exchange where the line terminates in contacts of a jack J and is provided with the usual line relay LR, line lamp LL and 110

- cut-off relay CO. The jack J is available to the initiating operator who extends the line circuit by means of the plug P whose contacts are connected by the strands of a trunk 5 or link circuit L' to the wipers of an automatic switch S. A second trunk or link circuit L² extends from the bank contacts of switch S through the contacts of a plug P² before the intermediate or tandem operator. 10 The circuit is further extended by inserting plug P² into a jack J² of a trunk or link circuit L³ which extends from the jack J² to a plug P³ before the distant operator at the exchange or office in which the called line L⁴ terminates in jack J³. The called line L⁴ extends from substation N and is provided with a line relay LR', a line lamp LL' and a cut-off relay CO', which are similar to those of the line L extending from 15 substation M. The conversational circuit established by extending the calling line circuit is indicated by heavy lines in Figs. 1, 2 and 3 of the diagram. The initiating operator, that is, the operator who has control 20 of the plug P, is provided with a sender SN which is operable to control the switch S over the strands of link circuit L¹ and subsequently to bring about the proper operation 25 of the line finder S² and either of the final switches S³ or S⁴, as the case may be, and then to display the proper indicating 30 lamps L⁵, L⁶, L⁷, L⁸, L⁹, L¹⁰, and L¹¹ of the annunciator mechanism which is before the tandem operator, that is, the operator having 35 control of plug P². The sender SN may be of any approved construction although preferably it is a key-board sender of the type shown in Lundell Patent No. 1,168,319, dated January 18, 1916. 40 The automatic switch S may also be of any approved type. It is here shown diagrammatically as comprising a set of wipers and associated bank contacts. United States Patent No. 1,103,623, granted July 14, 1914, 45 to Reynolds, illustrates a switch of the type which is preferably used to perform the functions of the switch S of the diagram. 50 The automatic line finding switch S² is also a switch of the type shown in said Reynolds patent and is shown in diagram as a set of wipers in association with bank contacts, the wipers being mounted upon a shaft 10 which is driven in one direction by a constantly rotating disk 11 and in the opposite 55 direction by a constantly rotating disk 12. The disks are brought into play in the one case by the energization of an advancing magnet AM and in the other case by the energization of a restoring magnet RM. In 60 each instance the magnet by its associated arm brings the lower flattened portion of the shaft 10 into frictional engagement with the disks to bring about the proper movement of the shaft. This switch is also provided with 65 a commutator 13 which is employed in vary-

ing the circuits in the operation of the switch and its associated mechanism.

The automatic switch S³ is preferably a switch of the rotary type, like that illustrated in United States Patent No. 1,146,583, granted July 13, 1915 to F. R. McBerty. In brief, the switch comprises a shaft 14 which is connected to a flexible magnetic disk 15 which may be drawn into frictional engagement with a constantly rotating disk 16 in response to the energization of the magnet 17. The shaft 14 carries springs 18, 19 and 20 through which circuit is extended to bank contacts 21, 22 and 23. These springs do not engage the bank contacts, but connection with the latter is brought about by brushes 24, 25 and 26 mounted on a vertical spindle 27 and engaged by the springs 18, 19 and 20, respectively. These brushes are tripped into engaging position by a series of 28 projections of which two, designated 28 and 29, are shown. These projections are mounted upon a vertical shaft 30 and are in spiral relation so as to bring about a tripping of the proper set of brushes in accordance with the rotary position of the shaft 30. This rotary position of the shaft is determined by bringing constantly rotating disk 31 into engagement with disk 32 upon the shaft 30 and maintaining the frictional engagement until the desired position of the shaft 30 is reached. This frictional engagement between the disks 31 and 32 is brought about by the energization of magnet 33. The magnet 34^b associated with the disk 15 is a braking magnet intended to bring about a speedy stopping of the disk when the desired point is reached. In addition to these parts the switch includes impulse contacts 34, 35 and 36, 37, which are operated by dogs 38 and 39 upon the shaft 27 and having operative relation with the notched racks 40 and 41.

The automatic switch S⁴ is similar in construction to the switch S³ and therefore need not be described in detail.

It may be pointed out at this point that in the subsequent description of the operation of the system, if any references are made to the parts of switch S⁴, those parts will be given designating characters similar to those of switch S³ but followed by the letter "a".

The annunciator illustrated in diagram in Fig. 3 consists of a series of lamps for each of the different designations that go to make up the complete designation of the called line. In the instance illustrated the lamp L⁵ is one of a series of lamps for the thousands digit of the called line. Likewise the lamp L⁶ is one of a series assigned to the hundreds digit of the called line. Similarly the lamp L⁷ is one of a series of lamps for indicating the tens digit of the called line. Again the lamp L⁸ is one of a series for indicating the units digit of the called line. 130

Where the call is for a subscriber upon a party line, then a lamp such as L^9 is used to indicate the particular party on the line. Where other information is to be furnished to the terminating operator, other lamps may be employed. Thus lamps L^{10} and L^{11} are employed to furnish such additional information. When the lamps of the entire indicator are displayed the designation of the called line may be readily read off by the tandem operator. Thus, if the number were 1234, that number would be read off from the first lamp of the thousands series, the second lamp of the hundreds series, the third lamp of the tens series and the fourth lamp of the units series. Furthermore, if the party to be signaled was the fourth party on a party line, then the fourth lamp of the party line series would be displayed.

This annunciator mechanism is of the type disclosed in United States Patent No. 1,117,511, granted November 17, 1914 to F. R. McBerty.

In the operation of the system many of the circuit changes are brought about by simple rotary switches termed sequence switches. The structure of these sequence switches includes in each instance a rotatable shaft having a series of disks of fiber or other insulating material secured thereto. On each side of each insulating disk is a circular conducting plate which is cut away or skeletonized so as to provide any desired arrangement of contacts. The plates on the opposite sides of the disk are electrically united by securing rivets. The rotatable disks are represented in the drawing in each instance by a long contact. A plurality of springs or brushes is provided for engagement with each pair of conducting disks and by means of these and by properly cutting away and arranging the plates on the insulating disks, any two or more brushes arranged for engagement with a disk may be electrically united at any stage of rotation of the shaft. In each instance, the positions of the sequence switch at which the various springs or brushes are in engagement with the rotatable disk are indicated by numerals placed adjacent to the long contacts of the diagram. Thus, in the case of sequence switch SS of Fig. 2 of the diagram, the shaft upon which the disks are mounted is designated 42 and the disks are designated 43 to 61, inclusive. All of these except the last make contact in the positions indicated by the numerals adjacent to them. In the case of the last contact, namely 61, which is shown with a projection on its upper face, the circuit is closed at all points between the positions indicated by the numerals adjacent to it and the circuit is open at those positions. It may be here pointed out that when in the subsequent description of the operation of the system

a circuit is traced through the contacts of a sequence switch, the designating numeral of the disk will be used followed by the number of the position of the switch at which the contact is made, the latter being 70 in parentheses. Thus, with the switch SS in the seventh position, a circuit through contact 56 would be indicated by "56 (7)". The structure of the sequence switch is such that the shaft, as shaft 42 of switch SS, 75 is driven from a constantly rotating shaft, as 61^a, through magnetic clutch disks, as 61^b and 62, which are brought into clutching engagement by the switch magnet, as SM. This same arrangement of disks and shaft is employed in each of the sequence switches and need not be further described. For convenience, however, the magnets of each of the sequence switches will be designated.

On Fig. 4 of the diagram three sequence switches SS¹, SS², and SS³ are shown. Switch SS¹ has an actuating magnet SM¹ and contacts 63 to 82, inclusive. The latter is a maintaining contact like the contact 90 61 of switch SS. The sequence switch SS² has an actuating magnet SM² and contacts 83 to 87, inclusive. This switch has for its function the allotting of the lamps of the annunciator to the different finder switch 95 circuits and the same has been termed in the diagram "lamp allotter". The sequence switch SS³ has an actuating magnet SM³ and contacts 88, 89 and 90, of which the last is a maintaining contact. This switch also 100 performs an allotting function. It allots or sets in waiting position the mechanism of the different cord finding circuits. The sequence switch SS⁴ is shown in Fig. 5 of the diagram. It is provided with an actuating magnet SM⁴ and contacts 91 to 102, inclusive, of which the last is a maintaining contact.

The sequence switches which control the annunciator circuits are shown in Fig. 6 of the diagram. Of these, the switch SS⁵ is provided with an actuating magnet SM⁵ and contacts 103 to 111, inclusive; switch SS⁶, with an actuating magnet SM⁶ and contacts 112 to 118, inclusive; switch SS⁷, 115 with an actuating magnet SM⁷ and contacts 119 to 127, inclusive; switch SS⁸, with an actuating magnet SM⁸ and contacts 128 to 135, inclusive; switch SS⁹, with an actuating magnet SM⁹ and contacts 136 to 143, inclusive; and switch SS¹⁰, with actuating magnet SM¹⁰ and contacts 144 to 151, inclusive. In each instance the last contact of the series is a maintaining contact.

It may be pointed out that the communicating or order wire circuit between the tandem operator and the terminating operator which is established by the operation of the switch mechanisms, extends from the tandem operator's head-set TO (Fig. 4) to the 130

terminating operator's head-set TO' (Fig. 3), the trunk wires 152 and 153 extending from the set TO to the moving contacts of the automatic switches S³ or S⁴, as the case 5 may be, and the trunk wires 154 and 155 extending from the bank contacts of one of the latter switches to the set TO'. In the instance illustrated these trunk wires 154 and 155 extend from the switch S³.

10 With this brief description of the principal portions of the diagram we may pass on to a description of its operation when putting through a call from substation M to substation N and in so doing the circuit connections and other portions of the apparatus will be more fully described.

If the party at substation M initiates a call by removing his receiver from its hook, a circuit will be closed for the line relay LR.

20 This circuit may be traced from the live pole of the battery 156 through the left-hand winding of relay LR, normal contact 157 of cut-off relay CO, over one limb of the line L, through the substation M, back over 25 the other limb of the line L, through normal contact 158 of cut-off relay CO and the right-hand winding of relay LR to ground. The resulting energization of relay LR will close its contact 159 and thereby complete 30 a circuit for line lamp LL from battery 160. Upon observing the lighting of lamp LL, the initiating operator, namely, the one having control of plug P, will insert said plug into jack J and close a circuit for cut-off 35 relay CO. This circuit may be traced from the live pole of battery 161 through protective resistance 162, plug and jack local contacts and the winding of cut-off relay CO to ground. The energization of relay 40 CO disconnects relay LR from the line and thereby deenergizes it and causes the circuit of lamp LL to be opened with a consequent extinguishment of the lamp. Upon the insertion of the plug P into jack J, the 45 tip and sleeve contacts connect the tip and sleeve strands of the line L and link circuit L'. As a result of this connection, transmission current is supplied from battery 163 through the windings 164 and 165 of a re- 50 peating coil to the opposite strands of the link circuit L' and thence over the line L to the transmitter of the substation M. The initiating operator is provided with the usual operator's set and by means of it and 55 a suitable listening key, (neither set nor key being shown) connects into the circuit of the calling line and obtains the order from the calling party in the usual way. As soon as the number of the called line is learned 60 the operator proceeds to manipulate the sender SN. Where the preferred type of sender is employed, she sets up the number of the called party upon the sender and sets it going to operate the other mechanisms to 65 bring about an extension of the calling cir-

cuit to the called line. Before this is done the contacts 166 and 167 are moved into circuit engagement with the conductors 168 and 169 by any suitable mechanism. Ordinarily this operation will be brought about 70 by a sequence switch associated with this part of the circuit. For the purposes of the present disclosure, however, it may be assumed to be performed by any suitable mechanism, or, if desired, by hand. The 75 first effect of the operation of the sender SN is to cause the automatic switch S to pick out an idle trunk L² extending to the desired distant office. In this switch structure the third wiper 170 and set of bank contacts 171 are used for test purposes in bringing about the proper selection. This switch structure and its operation is well known and for the purposes of the present disclosure need not be further described.

80 As soon as the switch S has brought about a connection between the strands of link circuit L' and those of link circuit L², a circuit is established which results in the starting of sequence switch SS. This circuit may 85 be traced from the live pole of battery 172 through sequence contact 50 (1 to 3), the winding of control relay CR, sequence contact 47 (1 to 2), protective resistance 173, tip strand of link circuit L², tip strand of link 90 circuit L¹, conductor 168, closed contact 174 of the sender SN, the winding of magnet 175 of the sender, conductor 169, contact 167, sleeve strands of link circuits L¹ and L², respectively, protective resistance 176, sequence contact 59 (1 to 3) to ground. The closing of this circuit energizes relay CR 95 and establishes a starting circuit for sequence switch SS. This starting circuit may be traced from the live pole of battery 177 through the winding of magnet SM, sequence contact 56 (1) and alternate contact 178 of relay CR to ground. The energization of magnet SM causes the sequence switch to advance from the first to the second position. 100 Its starting circuit is thereby broken at sequence contact 56 (1), but during its passage from one position to the other, the circuit of magnet SM is maintained through sequence contact 61, as before explained. In 105 consequence, the switch SS makes one complete step or advance from its initial position to its second position, and cannot be left at an intermediate point. The advance of this sequence switch to its second position 110 places ground at 59 upon the starting wire 179 and upon the hunting or test wire 180 of the line finder S². The placing of ground upon starting wire 179 completes a circuit for advancing relay AR which may be traced 115 from the live pole of battery 181 through the winding of relay AR, sequence contact 64 (1 to 12), sequence contact 64 (1 to 1½) conductor 179 and sequence contact 59 (2) to ground. The closing of this circuit ener- 120

125

130

135

gizes relay AR and the latter, by closing its alternate contact 182, establishes a starting circuit for sequence switch SS¹, which may be traced from the live pole of battery 183 through the magnet SM' of said switch, contacts of the test jack J⁴, sequence contact 69 (18 to 3), sequence contact 69 (1) and alternate contact 182 to ground. As a result, sequence switch SS¹ advances from position 1 to position 2. In this case a complete advance is brought about by the maintaining circuit through sequence contact 82 as heretofore described in connection with the switch SS. This advance of switch SS¹ 5 opens its starting circuit at sequence contact 69 (1) and in consequence it takes only one advance step. At sequence contact 66 (2) a circuit is completed for advancing magnet AM of the cord finder S². The complete circuit may be traced from the live pole of battery 184 through the winding of magnet AM, sequence contact 66 (2) and alternate contact 182 of relay AR to ground. Although the advance of switch SS¹ to position 20 has opened the initial starting circuit through wire 179 at sequence contact 64 (1 to 1 $\frac{1}{2}$), yet a maintaining circuit for relay AR is provided through closed contact 185, conductor 186, sequence contact 74 (1 to 2), conductor 187, commutator bar 188 and brush 189 to ground. This circuit is maintained until the switch S² makes a complete step, whereupon brush 189 rests upon an insulating segment and interrupts the maintaining circuit. In the meantime, however, an alternate maintaining circuit is provided for relay AR through sequence contact 64 (1 to 12), sequence contact 64 (1 $\frac{1}{2}$ to 2) and normal contact 190 to ground. This latter 25 contact is controlled by test relay TR which is brought into circuit with the test wiper 191 of switch S² as soon as sequence switch SS¹ moves to its second position. The test relay TR remains deenergized until the test wiper 191 engages a test contact 192 whose test wire 180 is connected to ground. As soon as such a contact is encountered, a circuit will be established for test relay TR which may be traced from the live pole of 30 battery 193 through the winding of relay TR, sequence contact 65 (2 to 12), sequence contact 65 (2 to 3), sequence contact 63 (2 to 3), test wiper 191, test contact 192, conductor 180 and sequence contact 59 (2) to ground. As a result of the energization of test relay TR by the closing of this circuit, its normal contact 190 is broken and the maintaining circuit for AR is thereby interrupted. As a consequence the circuit for 35 advancing magnet AM is interrupted at contact 182 and the further advance of the switch S² is discontinued. By reason of the position of the insulating segments in association with the commutator contact strip 40 188, an accurate full step of the switch is

secured in every instance. When the switch S² is thus stopped, pawl 194 associated with the armature of return magnet RM drops into a notch in the lower portion of shaft 10 and holds the switch S in its desired advanced position. As soon as relay TR is 45 energized, by reason of the test wiper 191 finding a grounded contact, it is maintained energized by a locking circuit extending from battery 193, sequence switch contact 65 (2 to 12), sequence switch contact 65 (2 to 3) and through alternate contact 190 to ground. 50 As soon as relay AR became deenergized as a result of the energization of test relay TR, a circuit for sequence switch SS' was 55 established. This circuit may be traced from the live pole of battery 183 through the winding of magnet SM', sequence contact 67 (2) and normal contact 182 to ground. In consequence of the closing of this circuit SS' advances from position 2 to position 60 3. The starting circuit is broken at sequence contact 67 (2). The closing of sequence contacts 63 (3), 65 (2 to 3) and 65 (3), establishes a starting circuit for sequence switch SS which may be traced from the live pole of battery 177 through the winding of magnet SM, sequence contact 58 (2 to 3), sequence contact 58 (2), conductor 195, bank contact 196 of switch S², wiper 197 of the 65 same switch, sequence contact 65 (3), sequence contact 65 (2 to 3), sequence contact 63 (2 to 3), test wiper 191, test contact 192, conductor 180 and sequence contact 59 (2) to ground. As a result, sequence switch SS advances to its third position, the starting circuit being broken at sequence contact 58 (2). 70 As a result of this advance of switch SS to position 3, relay AR is energized to bring about an advance of sequence switch SS' to position 4. The circuit for relay AR which is thus established extends from the live pole of battery 181 through the winding of relay AR, sequence contact 64 (1 to 12), sequence contact 64 (3 to 15), wiper 198 of switch S², bank contact 199 of the same switch, conductor 200, sequence contact 51 (3 to 5), sequence contact 51 (3) and alternate contact 178 to ground. It may be here pointed out that, whereas relay CR was initially energized over the circuit through the sender SN and included sequence contact 47 (1 to 2), just as soon as sequence switch SS moved to its second position an alternate path for relay CR was established by way of sequence contact 47 (2 to 3), closed contact 201 of relay CR, sequence contact 43 (2 to 3) and sequence contact 43 (2 to 3), through protective resistance 173 to the tip strand of link circuit L² in parallel to the initial path through sequence contact 47 (1 to 2). Consequently, at this time contact 178 is in its alternate position and relay AR is energized by the closing of the circuit just 80 traced. The energization of relay AR com- 85

- pletes a starting circuit for sequence switch SS' which may be traced from the live pole of battery 183 through sequence contact 69 (18 to 3), sequence contact 69 (3) and alternate contact 182, to ground. As a result, switch SS' is advanced to its fourth position and the initial starting circuit is interrupted at sequence contact 69 (3). As soon as switch SS' moves to its fourth position 5 a circuit is completed for sequence switch SS⁴ (Fig. 5). This circuit may be traced from the live pole of battery 202 through the winding of magnet SM⁴, conductor 203, sequence contact 74 (4), conductor 186, 10 closed contact 185, and thence to ground at alternate contact 178 of relay CR over the path previously traced as part of the energizing circuit of relay AR. For convenience, this path may be again traced 15 through sequence contact 64 (1 to 12), sequence contact 64 (3 to 15), wiper 198, bank contact 199, conductor 200, sequence contact 51 (3 to 5), sequence contact 51 (3) and alternate contact 178 to ground. The closing 20 of this circuit for switch SS⁴ causes the same to advance from its normal position to its zero position. In so doing sequence contact 94, which is closed between positions and open at positions of the sequence switch, momentarily connects conductors 204 and 205 25 and thereby momentarily short-circuits the magnet 175 of the sender SN. It will be remembered that the circuit through control relay CR and the magnet 175 of the sender, 30 extends through sequence contact 47 (2 to 3), closed contact 201, sequence contact 43 (2 to 3), sequence contact 43 (2 to 3) protective resistance 173, over the tip strands of the link circuits L², L¹, through the 35 sender magnet 175 and back over the sleeve strands of said link circuits to ground at sequence contact 59 (1 to 3). The circuit branch by which the sender magnet 175 is short-circuited, extends from sequence contact 40 45 43 (2 to 3) over impulse wire 206, bank contact 207 of cord finder S², wiper 208 of the same switch, conductor 205, closed sequence contact 94, conductor 204, sequence contact 66 (3½ to 12) and alternate contact 50 55 59 (1 to 3) of relay AR to ground. As before explained, this ground connection is but momentary. At the instant of its establishment the sender magnet 175 is deenergized and if the sender is set so as to cause the sequence switch SS⁴ to make but a single 60 65 advance step, then immediately contact 174 of the sender is opened and in consequence thereof control relay CR is deenergized and the path to ground through alternate contact 178 is broken and both relay AR and sequence magnet SM⁴ are deenergized. If the sender is set so as to allow further advances of the sequence switch SS⁴, then the latter proceeds to advance, each time 65 momentarily closing the connection to

ground and causing the sender magnet 178 to be deenergized as before. In the present case, the sender SN will not cause the sequence switch SS' to advance more than four steps, that is to say, farther than to 70 its third position. This is because there are but four groups of trunks 154, 155, to which the tandem operator's set TO may be connected. If we assume that the sender has been set so as to cause sequence switch SS⁴ 75 to move only one step, that is to say, to its zero position, then we will find that relays CR and AR and sequence magnet SM⁴ are deenergized in the manner just explained. The movement of sequence switch SS' to its 80 zero position connects the order wires 152 and 153 through sequence contacts 95 (0 to 1) and 96 (0 to 1) to the wipers 24 and 25, respectively, of switch S³. It will be seen that if the switch SS⁴ had moved to a second or third position in response to a different setting of the sender N, then the wires 152 and 153 would have been extended via sequence contacts 95 (2 to 3) and 96 (2 to 3) and conductors 209 and 210 to the 90 wipers 24^a and 25^a of switch S⁴. Thus the operation of the switch SS⁴ in response to the setting of the sender SN picks out the particular final switch that is to be brought into circuit and thereby performs the first 95 step in determining the group of conductors 154 and 155 which are to be brought into circuit. Having picked out the particular switch S³, it remains for subsequent operations to cause that switch to pick out contacts 21 and 22 of the desired group of conductors 154 and 155. In the type of switch shown, the next selection, which is commonly called brush selection, is brought about by the projections upon the shaft 30 100 105 which is rotated in response to the energization of the magnet 33. Impulses for the operation of this magnet come through sequence contact 98 (0 to 1). It will be seen that if the switch S⁴ had been selected then 110 115 120 125 130 135 140 145 150 155 160 165 170 175 180 185 190 195 200 205 210 215 220 225 230 235 240 245 250 255 260 265 270 275 280 quence contact 92 (0 to 16), conductor 212, normal contact 213 of relay 214, conductor 215, normal contact 216 of relay 217, conductor 218, sequence contacts 108 (N), 115 5 (N), 124 (N), 132 (N), 140 (N), 148 (N), conductor 219, sequence contact 79 (4 to 12), conductor 220, and normal contact 182 of relay AR to ground. As a result of the closing of this circuit, switch SS' moves 10 to its fifth position. As soon as this occurs, relay CR, relay AR and brush selecting magnet 33 are energized. The circuit by which relay CR is energized extends from the live pole of battery 172 through sequence 15 contact 50 (1 to 3), the winding of relay CR, sequence contact 47 (2 to 3), sequence contact 45 (2 to 3), sequence contact 45 (2 to 3), conductor 221, bank contact 222 of switch S², wiper 223 of the same 20 switch, conductor 224, sequence contact 78 (5), conductor 225, sequence contact 93 (0 to 16), conductor 226, normal contact 227 of relay 214, conductor 228, normal contact 229 of relay 217, conductor 230, sequence 25 contacts 109 (N), 116 (N), 125 (N), 133 (N), 141 (N), 149 (N), conductor 205, wiper 208 of switch S², bank contact 207, conductor 206, sequence contact 43 (2 to 3), sequence contact 43 (2 to 3), protective 30 resistance 173, and thence, as before, over the tip side of the link circuits L', L², through the sender magnet 175 and back over the sleeve side of the circuits L', L², and through protective resistance 176 and 35 sequence contact 59 (1 to 3) to ground. The energizing circuit for relay AR is established as before when alternate contact 178 of relay CR is closed. The energizing circuit for the brush selecting magnet 33 of 40 switch S³ extends from the live pole of battery 231 through the winding of magnet 33, sequence contact 98 (0 to 1), conductor 232, sequence contact 74 (5), conductor 186, closed contact 185 of relay AR, and thence 45 over the path to ground at alternate contact 178 of relay CR as before traced. As a result of the closing of these circuits for relays CR and AR and magnet 33, they and the sender magnet 175 are energized. 50 The energization of magnet 175 operates the sender one step and the energization of magnet 33 advances the shaft 30. As the latter advances, it actuates lever 233 to close circuit at points 234 and 235 between conductors 236 and 237, thereby connecting impulse wire 205 to ground through wire 204, sequence contact 66 (3½ to 12) and alternate contact 182 of relay AR. The grounding of the impulse wire in this way causes magnet 175 of the sender SN to be deenergized. Thus, as the brush tripping shaft 30 advances step by step, sender magnet 175 is deenergized in response to the repeated momentary closings of the short-circuiting path 55 until shaft 30 has advanced to a position corresponding to the setting of the sender. When this point is reached, contact 174 of the sender will open the circuit as before and relays CR and AR and brush selection magnet 33 will be deenergized. This operation completes the act of setting the shaft 30 so as to bring the proper projection 28 into the path of the wipers or brushes 24 and 25, which are to be used in extending the circuit of the order wires 152 and 153. 70

The next operation is to bring about an advance of the wipers of the switch S³. Before this advance can take place, sequence switch SS' must advance to position six. It may be here pointed out that the switch S³ is provided with off-normal contacts 238, 239 and 240. As soon as the shaft 30 moves from its normal position, contacts 238 and 239 are opened and contacts 239 and 240 are closed. The closing of the latter contacts completes a circuit for relay 214 which may be traced from the live pole of battery 241 through the winding of relay 214, conductor 242 and closed off-normal contacts 240 and 239 to ground. The energization of 80 relay 214 brings about a change of connections which insures a circuit for the control relay CR at this stage of the operation. Before such circuit is established, however, switch SS' must be advanced. The circuit for advancing switch SS' may be traced from the live pole of battery 183 through sequence contact 68 (5), conductor 243, alternate contact 213, normal contact 216, conductor 218, sequence contacts 108 (N), 115 85 (N), 124 (N), 132 (N), 140 (N) and 148 (N), conductor 219, sequence contact 79 (4 to 12), conductor 220, and normal contact 182 to ground. As a result of this movement of sequence switch SS' to the sixth position, relays CR and AR and wiper actuating magnet 17 are energized. The energizing circuit for relay CR extends from the live pole of battery 172 through sequence 90 contact 50 (1 to 3), the winding of relay CR, sequence contact 47 (2 to 3), sequence contact 45 (2 to 3), sequence contact 45 (2 to 3), conductor 221, bank contact 222, wiper 223, conductor 224, sequence contact 78 (6), conductor 244, alternate contact 227, conductor 228, normal contact 229, conductor 230, sequence contacts 109 (N), 116 (N), 125 (N), 133 (N), 141 (N), 149 (N), conductor 205, wiper 208, bank contact 207, conductor 206, sequence contact 43 (2 to 3), sequence contact 43 (2 to 3), protective resistance 173, tip strands of link circuits L² and L¹, the winding of sender magnet 175, sleeve strands of link circuits L¹ and L², protective resistance 176, and sequence contact 59 (1 to 3). The energizing of relay CR as a result of closing this circuit, closes the circuit for relay AR which extends, as before traced, to ground at alternate contact 178 of relay CR. The closing of contact 185 100

of relay AR brings switch magnet 17 into circuit by closing a path which may be traced from the live pole of battery 245 through the winding of magnet 17, conductor 246, sequence contact 99 (0 to 1), conductor 247, sequence contact 73 (6), conductor 186 and closed contact 185 to the circuit of relay AR which goes to ground at alternate contact 178 of relay CR, as previously traced. The closing of this circuit for magnet 17 causes it to bring about a clutching engagement between the constantly rotating disk 16 and the coöperating disk 15 to rotate shaft 14 which carries the wipers or brushes 24, 25 and 26 of the switch S³. As the wipers advance, only those are in position to engage the bank contacts 21, 22 and 23, which have been tripped by a properly set projection on the shaft 30. As the switch wipers advance, the actuating arms 38 and 39 pass over the associated racks 40 and 41 to actuate the contacts 34 and 35, in the one case, and 36 and 37, in the other, to short-circuit the sender magnet 175 in a way similar to that previously described in connection with contacts 234 and 235 associated with the brush selecting magnet 33, and contact 94 associated with the sequence switch SS⁴. These impulse contacts 34, 35 and 36, 37 are arranged so as to close circuit between conductors 204 and 205 in a way similar to that brought about by contacts 234 and 235 associated with the brush selecting magnet 33. The path in bridge of conductors 204 and 205 may be traced from conductor 204 through conductor 248, conductor 249, contacts 34 and 35, conductor 250, conductor 251, sequence contact 101 (0 to 2), and conductor 252 to conductor 205. It may be pointed out that if the sequence switch had been in position to close sequence contact 101 (1 to 3), then the circuit would have included impulse contacts 36, 37, conductor 253, conductor 254, sequence contact 101 (1 to 3) and conductor 252. It may also be pointed out that contacts 34^a, 35^a, 36^a, and 37^a, of switch S⁴, are connected in parallel with the corresponding contacts of switch S³. From this description, it will be seen that when switch S³ is advancing, its contacts 34 and 35 will not be closed until the end of the arm 38 engages the teeth of the rack 40. When this occurs there will be an intermittent closing of the contacts 34, 35, to intermittently short-circuit the magnet 175 of the sender SN. For convenience, the short-circuiting path may be traced from sequence contact 43 (2 to 3) over impulse wire 206, bank contact 207, wiper 208 of switch S², conductor 205, conductor 252, sequence contact 101 (0 to 2), conductors 251 and 250, contacts 35 and 34, conductors 249, 248, 204, sequence contact 66 (3₁ to 12) and alternate contact 182 to ground. The intermittent closing of this grounded branch will bring about intermittent energizations of magnet 175 of the sender and when the requisite number of advance steps have been made, as determined by the setting of the sender, then the contact 174 of the sender will be opened and relays CR and AR and motor magnet 17 deenergized. This will, however, only occur when the wipers 24 and 25 of the switch S³ have been advanced to the desired bank contacts 21 and 22, and by reason of their tripped condition, brought into electrical contact with those bank contacts. When this occurs, the circuit of order wire conductors 152 and 153 will be completed through the springs 18 and 19, wipers 24 and 25 and bank contacts 21 and 22 of switch S³, and thence through the order wire conductors 154 and 155 running to the desired terminating operator's set TO'. The next operation is the advance of sequence switch SS' from position 6 to position 7. This is brought about upon the opening of contact 174 of the sender with the consequent deenergization of relays CR, AR and magnet 17. It may here be pointed out that the rotary switch S³ is provided with off-normal contacts 255, 256 and 257, which are actuated whenever the wipers of switch S³ are rotated from normal position. As the switch moves from normal, contacts 255 and 256 are opened and contacts 256 and 257 are closed. The closing of the latter contacts energizes relay 217 by closing a circuit which may be traced from the live pole of battery 258 through the winding of relay 217, conductor 259 and contacts 257 and 256 to ground. This connection is also provided with a parallel path through similar contacts of switch S⁴. The energization of relay 217 has to do with the establishing of circuits for the subsequent advance of sequence switch SS' and the energization of relay CR. The circuit by which sequence switch SS' is advanced to its seventh position, extends from the live pole of battery 183 through the winding of magnet SM', sequence contact 68 (6), conductor 211, alternate contact 216, conductor 218, sequence contacts 108 (N), 115 (N), 124 (N), 132 (N), 140 (N), 148 (N), conductor 219, sequence contact 79 (4 to 12), conductor 220 and normal contact 182 to ground. Sequence switch SS' is thus moved to position 7. As soon as this takes place, a circuit is established for energizing control relay CR. This circuit extends from the live pole of battery 172, through sequence contact 50 (1 to 3), the winding of relay CR, sequence contact 47 (2 to 3), sequence contact 45 (2 to 3), sequence contact 45 (2 to 3), conductor 221, bank contact 222, wiper 223, conductor 224, sequence contact 78 (7), conductor 225, alternate contact 229, conductor 230, sequence contacts 109 (N), 116 (N), 125 (N), 133 (N), 141 (N), 149 (N), conductor 205, 13

wiper 208, bank contact 207, conductor 206, sequence contact 43 (2 to 3), sequence contact 43 (2 to 3), resistance 173, tip strands of link circuits L^2 and L^1 , the winding of 5 sender magnet 175, the sleeve side of link circuits L^1 and L^2 , resistance 176 and sequence contact 59 (1 to 3), to ground. The resulting energization of relay CR closes alternate contact 178 to ground and again energizes relay AR in the manner heretofore 10 described. At the same time, magnet SM^5 of sequence switch SS^5 is brought into a circuit which may be traced from the live pole of battery 260 through the winding 15 of magnet SM^5 , conductor 261, sequence contact 73 (7), conductor 186 and closed contact 185 to the circuit of relay AR which goes to ground at alternate contact 178 of relay CR. The result of closing the circuit 20 of magnet SM^5 is to cause sequence switch SS^5 to advance from its normal position to its zero position. In doing so its contact 110 which is opened at positions of the sequence switch and closed between positions 25 as indicated by the numerals adjacent to it, makes a momentary connection between conductors 204 and 205, by which the usual ground connection is established to short-circuit the sender magnet 175. A reference 30 to the connection of conductors 236 and 237 in the case of the brush selection, and of the conductors 248 and 252 in the case of the group selection, will show that it is the same conductors 204 and 205 which bring about 35 the short-circuiting of the sender magnet whenever they are electrically connected. It will therefore not be necessary to again trace this path to ground. If the sender is set so as to cause the switch SS^5 to make only 40 one advance step, then the sender contact 174 will be opened as a result of the first impulse transmitted by the closing of contact 110, and the relays CR and AR and the magnet SM^5 will be deenergized. The result of such deenergization will be to stop 45 the switch SS^5 in its zero position. It may be assumed, however, in the present case, that the sender is set so as to require five impulses by the contact 110 before this 50 breaking down of the fundamental circuit is brought about. In such case the switch SS^5 will be moved into position 4, which connects the thousands lamp L^5 into circuit. This lamp L^5 will be the one corresponding 55 to the thousands digit of the called number as set up on the sender SN.

The breaking down of the fundamental circuit, as just explained, will cause sequence switch SS^2 to advance from its seventh position 60 to its eighth position. The circuit by which this is accomplished may be traced from the live pole of battery 183 through the winding of magnet SM^2 , sequence contact 68 (7), conductor 243, sequence contacts 108 (0 to 16), 115 (N), 124 (N), 132 (N), 140 (N), 148 (N), conductor 219, sequence contact 79 (4 to 12), conductor 220, normal contact 182 to ground. As soon as sequence switch SS^2 advances to its eighth position, relay CR will be again energized 70 with a resulting energization of relay AR and thereupon an energization of magnet SM^6 of sequence switch SS^6 . The circuit by which relay CR is energized may be traced from the live pole of battery 172 through sequence contact 50 (1 to 3), the winding of relay CR, sequence contact 47 (2 to 3), sequence contact 45 (2 to 3), sequence contact 45 (2 to 3), conductor 221, bank contact 222, wiper 223, conductor 224, sequence contact 78 (8), conductor 244, sequence contacts 109 (0 to 16), 116, (N), 125 (N), 133 (N), 141 (N), 149 (N), conductor 205, wiper 208, bank contact 207, conductor 206, sequence contact 43 (2 to 3) and thence over 85 the link circuit strands L^2 and L^1 through the sender magnet 175 and back to ground at sequence contact 59 (1 to 3). As before, the closing of alternate contact 178 of relay CR, energizes relay AR and the latter, by 90 closing its contact 185, completes an energizing circuit for the associated switch magnet, which in this case is the magnet SM^6 of sequence switch SS^6 . The circuit of the latter extends from the live pole of battery 95 262, through the winding of magnet SM^6 , conductor 263, sequence contact 73 (8), conductor 186 and closed contact 185 to the circuit of relay AR which is connected to ground at alternate contact 178 of relay CR. 100 As before, the energization of the motor magnet of the sequence switch causes it to advance and as it advances, its contact 117, which is open at positions and closed between positions momentarily short-circuits 105 the sender magnet 175 and these short-circuiting impulses continue until the sender has advanced far enough to open its contact 174 to break down the fundamental circuit and cause the consequent deenergization of 110 relays CR and AR and magnet SM^6 . In the present instance, it may be assumed that the setting of the sender which brings about the desired advance of sequence switch SS^6 , is such as to bring it into its third position. In certain types of trunking arrangements, this operation is necessary to pick out a proper group of trunks, and, accordingly, in the present instance, where the sender is assumed to be of the type where such selection is necessary, the advance of the switch SS^6 does not cause the lighting of a lamp since the position of the switch does not in any way correspond to a digit of the number which the tandem operator is to read 115 off to the terminating operator in giving her the number of the called line. In the present instance, this switch merely comes into play in establishing the complete circuit for the associated thousands and hun- 120 125 130 135

dreds lamps. As soon as switch SS^6 has stopped as a result of the deenergization of relays CR and AR, a circuit for sequence switch SS' is established for the purpose of 5 advancing said switch SS' to its ninth position. The circuit for bringing about this result extends from the live pole of battery 183 through the winding of magnet SM' , sequence contact 68 (8), conductor 211, sequence contacts 115 (0 to 16), 124 (N), 132 (N), 140 (N), 148 (N), conductor 219, sequence contact 79 (4 to 12), conductor 220 and normal contact 182 to ground. The 10 advance of sequence switch SS' to the ninth position results in establishing a new energizing circuit for relay CR, with a consequent energization of relay AR and motor magnet SM' of the next sequence switch SS^7 . The energizing circuit for relay CR 15 extends from the live pole of battery 172 through the winding of relay CR, sequence contact 47 (2 to 3), sequence contact 45 (2 to 3), sequence contact 45 (2 to 3), conductor 221, bank contact 222, wiper 223, conductor 224, sequence contacts 78 (9), conductor 225, sequence contacts 116 (0 to 16), 125 (N), 133 (N), 141 (N), 149 (N), conductor 205, wiper 208, bank contact 207, conductor 206, sequence contact 43 (2 to 3), 20 sequence contact 43 (2 to 3), resistance 173, to the tip side of the link circuits L^2 , L^1 , through the sender magnet 175 and back over the sleeve side of link circuits L^1 and L^2 , to ground at sequence contact 59 (1 to 3). As before, the energizing of relay CR 25 causes the energization of relay AR and a circuit is provided for the associated switch magnet which in the present instance is the magnet SM' of switch SS^7 . The circuit for said magnet extends from the live pole of battery 264 through the winding of magnet SM' , conductor 265, sequence contact 73 (9), conductor 186, closed contact 185 and thence to ground at alternate contact 178 of relay CR as before traced. Again 30 the advance of the sequence switch connects conductors 204 and 205 momentarily by a bridging contact 126 which is open at the positions of the switch and closed between its positions. This contact 126 short-circuits the sender magnet 175, as in the case of the corresponding contacts of the preceding switches SS^5 and SS^6 , and the advance continues until contact 174 of the 35 sender is opened. This, as before explained, will depend upon the setting of the sender. If it be assumed that the sender is set so as to advance the switch SS^7 to its third position, in such instance the proper lamp L^6 will be connected into circuit. The lamp in this instance will correspond to the hundreds digit of the called line.

Upon the breaking down of the fundamental circuit in this instance, the relays 40 CR, AR and the magnet SM' will be de-

energized and immediately upon the deenergization of relay AR, sequence switch SS' will be advanced from its ninth position to its tenth position. The circuit for bringing about this result may be traced 45 from the live pole of battery 183 through the winding of magnet SM' , sequence contact 68 (9), conductor 243, sequence contacts 124 (0 to 16), 132 (N), 140 (N), 148 (N), conductor 219, sequence contact 79 (4 to 12), conductor 220 and normal contact 182 to ground. As soon as switch SS' has thus advanced to its tenth position, relay CR will be again energized with a resulting energization of relay AR and of a new switch magnet, namely, magnet SM^8 of sequence switch SS^8 . The circuit for energizing relay CR extends as before over conductors 221 and 224, thence through sequence contact 78 (10), conductor 244, sequence contacts 125 (0 to 16), 133 (N), 141 (N), and 149 (N), and conductors 205 and 206 to the sleeve side of the link circuits L^2 and L^1 and thence through sender magnet 175 and over the sleeve side of link 50 circuits L^1 and L^2 to ground at sequence contact 59 (1 to 3). The closing of alternate contact 178 of relay CR, as before, energizes relay AR and completes the ground connection for the energization of the associated switch motor magnet, namely, the magnet SM^8 . The circuit by which the latter magnet is energized extends from the live pole of battery 266 through the winding of magnet SM^8 , conductor 267, sequence 55 contact 72 (10), conductor 186 and closed contact 185 to the circuit of relay AR, which, as before pointed out, is closed to ground at alternate contact 178 of relay CR. Like its predecessors, the sequence switch SS^8 momentarily connects conductors 204 and 205 as the switch advances, and thereby momentarily and intermittently short-circuits the sender magnet 175, as before explained. The contact 134 of switch SS^8 performs this short-circuiting function. Like the corresponding contacts of the other switches, it is open in the switch positions and closed between those positions. It may be assumed that the sender is set to stop 60 switch SS^8 upon its ninth position. Under this assumption, as soon as the ninth position is reached, the fundamental circuit will be broken down by the opening of sender contact 174, as before. The result 65 will be the deenergization of relays CR and AR and of motor magnet SM^8 .

As soon as sequence switch SS^8 is brought to rest, sequence switch SS' is advanced from its tenth position to its eleventh position. This is brought about by the deenergization of relay AR, which followed the breaking down of the fundamental circuit. The circuit by which this advance of switch SS' is brought about extends from the live 70 conductor 219 through sequence contact 79 (4 to 12), conductor 220 and normal contact 182 to ground. As soon as switch SS' has thus advanced to its eleventh position, relay CR will be again energized with a resulting energization of relay AR and of a new switch magnet, namely, magnet SM^9 of sequence switch SS^9 . The circuit for energizing relay CR extends as before over conductors 221 and 224, thence through sequence contact 78 (10), conductor 244, sequence contacts 125 (0 to 16), 133 (N), 141 (N), and 149 (N), and conductors 205 and 206 to the sleeve side of the link circuits L^2 and L^1 and thence through sender magnet 175 and over the sleeve side of link 75 circuits L^1 and L^2 to ground at sequence contact 59 (1 to 3). The closing of alternate contact 178 of relay CR, as before, energizes relay AR and completes the ground connection for the energization of the associated switch motor magnet, namely, the magnet SM^9 . The circuit by which the latter magnet is energized extends from the live pole of battery 266 through the winding of magnet SM^9 , conductor 267, sequence 80 contact 72 (10), conductor 186 and closed contact 185 to the circuit of relay AR, which, as before pointed out, is closed to ground at alternate contact 178 of relay CR. Like its predecessors, the sequence switch SS^9 momentarily connects conductors 204 and 205 as the switch advances, and thereby momentarily and intermittently short-circuits the sender magnet 175, as before explained. The contact 134 of switch SS^9 performs this short-circuiting function. Like the corresponding contacts of the other switches, it is open in the switch positions and closed between those positions. It may be assumed that the sender is set to stop 85 switch SS^9 upon its ninth position. Under this assumption, as soon as the ninth position is reached, the fundamental circuit will be broken down by the opening of sender contact 174, as before. The result 90 will be the deenergization of relays CR and AR and of motor magnet SM^9 .

As soon as sequence switch SS^9 is brought to rest, sequence switch SS' is advanced from its eleventh position to its twelfth position. This is brought about by the deenergization of relay AR, which followed the breaking down of the fundamental circuit. The circuit by which this advance of switch SS' is brought about extends from the live 95 conductor 219 through sequence contact 79 (4 to 12), conductor 220 and normal contact 182 to ground. As soon as switch SS' has thus advanced to its twelfth position, relay CR will be again energized with a resulting energization of relay AR and of a new switch magnet, namely, magnet SM^10 of sequence switch SS^{10} . The circuit for energizing relay CR extends as before over conductors 221 and 224, thence through sequence contact 78 (10), conductor 244, sequence contacts 125 (0 to 16), 133 (N), 141 (N), and 149 (N), and conductors 205 and 206 to the sleeve side of the link circuits L^2 and L^1 and thence through sender magnet 175 and over the sleeve side of link 100 circuits L^1 and L^2 to ground at sequence contact 59 (1 to 3). The closing of alternate contact 178 of relay CR, as before, energizes relay AR and completes the ground connection for the energization of the associated switch motor magnet, namely, the magnet SM^{10} . The circuit by which the latter magnet is energized extends from the live pole of battery 266 through the winding of magnet SM^{10} , conductor 267, sequence 105 contact 72 (10), conductor 186 and closed contact 185 to the circuit of relay AR, which, as before pointed out, is closed to ground at alternate contact 178 of relay CR. Like its predecessors, the sequence switch SS^{10} momentarily connects conductors 204 and 205 as the switch advances, and thereby momentarily and intermittently short-circuits the sender magnet 175, as before explained. The contact 134 of switch SS^{10} performs this short-circuiting function. Like the corresponding contacts of the other switches, it is open in the switch positions and closed between those positions. It may be assumed that the sender is set to stop 110 switch SS^{10} upon its ninth position. Under this assumption, as soon as the ninth position is reached, the fundamental circuit will be broken down by the opening of sender contact 174, as before. The result 115 will be the deenergization of relays CR and AR and of motor magnet SM^{10} .

As soon as sequence switch SS^{10} is brought to rest, sequence switch SS' is advanced from its twelfth position to its thirteenth position. This is brought about by the deenergization of relay AR, which followed the breaking down of the fundamental circuit. The circuit by which this advance of switch SS' is brought about extends from the live 120 conductor 219 through sequence contact 79 (4 to 12), conductor 220 and normal contact 182 to ground. As soon as switch SS' has thus advanced to its thirteenth position, relay CR will be again energized with a resulting energization of relay AR and of a new switch magnet, namely, magnet SM^{11} of sequence switch SS^{11} . The circuit for energizing relay CR extends as before over conductors 221 and 224, thence through sequence contact 78 (10), conductor 244, sequence contacts 125 (0 to 16), 133 (N), 141 (N), and 149 (N), and conductors 205 and 206 to the sleeve side of the link circuits L^2 and L^1 and thence through sender magnet 175 and over the sleeve side of link 125 circuits L^1 and L^2 to ground at sequence contact 59 (1 to 3). The closing of alternate contact 178 of relay CR, as before, energizes relay AR and completes the ground connection for the energization of the associated switch motor magnet, namely, the magnet SM^{11} . The circuit by which the latter magnet is energized extends from the live pole of battery 266 through the winding of magnet SM^{11} , conductor 267, sequence contact 72 (10), conductor 186 and closed contact 185 to the circuit of relay AR, which, as before pointed out, is closed to ground at alternate contact 178 of relay CR. Like its predecessors, the sequence switch SS^{11} momentarily connects conductors 204 and 205 as the switch advances, and thereby momentarily and intermittently short-circuits the sender magnet 175, as before explained. The contact 134 of switch SS^{11} performs this short-circuiting function. Like the corresponding contacts of the other switches, it is open in the switch positions and closed between those positions. It may be assumed that the sender is set to stop 130 switch SS^{11} upon its ninth position. Under this assumption, as soon as the ninth position is reached, the fundamental circuit will be broken down by the opening of sender contact 174, as before. The result will be the deenergization of relays CR and AR and of motor magnet SM^{11} .

5 pole of battery 183 through the winding of magnet SM', sequence contact 68 (10), conductor 211, sequence contacts 132 (0 to 16), 140 (N), 148 (N), conductor 219, sequence contact 79 (4 to 12), conductor 220 and normal contact 182 to ground. As soon as this advance has taken place, relay CR will be again energized by a circuit including conductors 221 and 224, as before, thence 10 by way of sequence contact 78 (11), conductor 225, sequence contact 133 (0 to 16), 141 (N), 149 (N), conductors 205 and 206 to the tip side of the link circuits L² and L¹, thence through the winding of sender 15 magnet 179 and back over the sleeve side of the said link circuits to ground at sequence contact 59 (1 to 3). Following this, relay AR is energized by reason of the closure of alternate contact 178 of relay 20 CR. At the same time magnet SM⁹ of sequence switch SS⁹ is brought into circuit. This circuit extends from the live pole of battery 268 through the winding of magnet SM⁹, conductor 269, sequence contact 72 25 (11), conductor 186 and closed contact 185 to the circuit of relay AR and thence over said circuit to ground at alternate contact 178. The impulse contact 142 of sequence switch SS⁹ is open at the positions of the switch and closed between them, so that like the other impulse contacts it will momentarily connect conductors 204 and 205, and thereby momentarily intermittently short-circuit sender magnet 175. If it be 30 assumed that the sender is set so as to stop the switch SS⁹ in position 5, then as soon as said switch reaches said position, sender contact 174 will be opened to break down the fundamental circuit and deenergize relays CR and AR and magnet SM⁹ in the manner heretofore repeatedly explained. 35

40 As soon as the fundamental circuit is thus broken down sequence switch SS' will advance from its eleventh position to its twelfth position. The circuit for bringing about this advance extends from the live pole of battery 183 through the winding of magnet SM', sequence contact 68 (11), conductor 243, sequence contacts 140 (0 to 16), 148 (N), conductor 219, sequence contact 79 (4 to 12) and normal contact 182 to ground. As soon as this advance of switch SS' to position 12 has taken place, relays CR and AR and magnet SM¹⁰ will be energized. 45

50 The energizing circuit of relay CR extends, as before, over conductors 221 and 224 and thence by way of sequence contact 78 (12), conductor 244, sequence contacts 141 (0 to 16), 149 (N) and conductors 205 and 206 to the tip strands of link circuits L², L¹, thence through the winding of sender magnet 175 and back over the sleeve strands of said link circuits to ground at sequence contact 59 (1 to 3). The resulting energization of relay CR by closing alternate contact 178

55 brings about the energization of relay AR and the latter by closing its contact 185 brings sequence magnet SM¹⁰ into circuit. The latter circuit extends from the live pole of battery 270 through the winding of magnet SM¹⁰, conductor 271, sequence contact 72 (12), conductor 186 and closed contact 185 to the circuit of relay AR, which, as before pointed out, is closed at alternate contact 178 of relay CR. The sequence switch SS¹⁰ 60 has a contact 150, which is open at the positions of the switch and closed between these positions and this impulse contact intermittently connects conductors 204 and 205 as the switch advances. These connections 65 of conductors 204 and 205, as before, short-circuit the sender magnet 175 and continue to do so according to the setting of the sender. When the desired position of the switch SS¹⁰ is reached, that is, the position 70 corresponding to the setting of the sender, then contact 174 of the sender is opened and relays CR and AR are deenergized with a resulting deenergization of magnet SM¹⁰ of sequence switch SS¹⁰. If it be assumed that 75 the sender is set so as to stop the switch SS¹⁰ in position 1 then it will be seen that party line lamp L⁹ is brought into connection by the resulting advance of the switch. Advances to other positions may be used to 80 bring in other indicating lamps. For instance, if the switch be left in positions zero or 5, then lamp L¹⁰ would be brought into circuit. Likewise in positions zero to 4 inclusive, lamp L¹¹ would be brought into 85 circuit.

90 The next piece of mechanism to be operated is the sequence switch SS, which moves into position 4 out of position 3, which it has occupied during the transmission of impulses in connection with the sender SN. The circuit for the sequence switch SS may be traced from the live pole of battery 177 through the winding of magnet SM, sequence contact 58 (2 to 3), sequence contact 58 (3), conductor 272, bank contact 273 of switch S², wiper 274, conductor 275, sequence contact 148 (0 to 16), conductor 219, sequence contact 79 (4 to 12), conductor 220 and normal contact 182 to ground. The 95 sender SN has now completed its required operations in connection with the particular call under consideration and it is restored to normal position and contacts 166 and 167 close with contacts 276 and 277 so as to complete the strands of link circuit L'. This release of the sender and movement of the contacts 166 and 167 may be automatic, or, for the purposes of the present disclosure, the same may be considered as performed 100 by hand. As soon as the contacts 166 and 167 complete the strands of the link circuit L', a circuit is completed for relay 278 which may be traced from battery 279 through sequence contact 45 (4 to 17), sequence con- 105

- tact 45 (4 to 5), the winding of relay 278, the tip strands of link circuits L^2 and L^1 , including engaged contacts 166 and 276 and repeating coil winding 289 to ground at 281. The resulting energization of relay 278 completes a circuit for the double wound relay 282 which may be traced from battery 279 through sequence contact 45 (4 to 17), sequence contact 45 (4 to 5), the winding of relay 278, sequence contact 44 (4), closed contact 283 of relay 278, sequence contact 48 (4 to 5), sequence contact 48 (4 to 5), and the left-hand winding of relay 282 to ground. The resulting energization of relay 282 completes a locking circuit for said relay which may be traced from the live pole of battery 284 through the right-hand winding of relay 282, conductor 285, sequence contact 58 (4 to 8) sequence contact 58 (4 to 8), conductor 195, sequence contact 57 (4 to 8), sequence contact 57 (4 to 8), conductor 286, and closed contact 287 to ground. The completion of the locking circuit just traced results in placing ground upon the conductor 195. It thereby completes a circuit for test relay TR which may be traced from the live pole of battery 193 through the winding of relay TR, sequence contact 65 (2 to 12), sequence contact 65 (12 to 15), wiper 197 of switch S^2 , bank contact 196 and conductor 195 to ground at closed contact 287 of relay 282. The energizing of relay TR closes a starting circuit for sequence switch SS' which thereupon moves from position 12 to position 13. The circuit by which this latter movement is brought about may be traced from the live pole of battery 183 through the winding of magnet SM', sequence contact 67 (12) and closed contact 190 of relay TR to ground. When the sequence switch SS' gets into position 13, it cannot be advanced farther until the so-called lamp allotter or master-switch mechanism comprising the sequence switch SS² comes into play. If the sequence switch SS² be in the position illustrated, that is, in a position in which it, so to speak, rests upon the particular finder circuit under consideration, then a starting circuit for sequence switch SS' will be at once established and without an advance movement of the sequence switch SS². The function of the lamp allotter mechanism is to test out the different circuits associated with the finders S^2 until it engages one whose sequence switch SS' is in position 13. When it encounters such a circuit the sequence switch SS² of the allotter comes to rest. In this testing operation the test relay TR' defines the point at which the sequence switch SS² shall come to rest. As soon as sequence switch SS' moves into position 13, a circuit is established for relay AR which may be traced from the live pole of battery 181 through the winding of relay AR, sequence contact 65 (13 to 15), sequence contact 65 (12 to 15), wiper 197, bank contact 196, conductor 195, sequence contact 57 (4 to 8), sequence contact 57 (4 to 8), conductor 286 and closed contact 287 to ground. The resulting energization of relay AR closes contact 185 and thereby places ground upon conductor 186. If the lamp allotter be in the position illustrated in the drawing, then as soon as sequence switch SS' moves into position 13, relay TR' will be energized by the closing of a circuit which may be traced from the live pole of battery 288 through the winding of relay TR', sequence contact 84 (1), conductor 289, resistance 290, sequence contact 72 (13 to 15), to conductor 186 which is grounded by reason of the energization of relay AR, as before explained. The resulting energization of relay TR' closes alternate contact 291 and thereby establishes a starting circuit for sequence switch SS' which may be traced from the live pole of battery 183 through the winding of magnet SM', sequence contact 68 (13), sequence contact 87 (1), alternate contact 291, sequence contact 66 (13) and alternate contact 182 to ground. As a result of the closing of this circuit, sequence switch SS' moves from position 13 to position 15. If it be assumed that the allotter sequence switch SS² be in some other position than that illustrated, then as soon as sequence switch SS' moves into position 13, a starting circuit will be established for sequence magnet SM², which may be traced from the live pole of battery 272 through the winding of magnet SM², normal contact 291 of relay TR', sequence contact 66 (13), and alternate contact 182 to ground. The closing of this circuit will cause the switch SS² to advance. As it advances, the winding of relay TR' is brought successively into circuit engagement with branches like that through position 1 and conductor 289. As soon as a grounded branch is encountered, relay TR' is energized to interrupt the circuit of magnet SM² and prevent the further advance of the switch. The test relay TR' is short-circuited by sequence contact 85 in all positions of the switch except positions 1, 4, 7, 11, 14 and 17, indicated by the numerals adjacent to it. Thus a full advance of the switch to these positions is insured. As soon as sequence switch SS' moves through position 14 and into position 15, battery connections are supplied to the annunciator lamps. Thus lamp L^5 will be supplied by current from battery 292 over a circuit which may be traced from the live pole of battery 292 through sequence contact 70 (14 to 15), conductor 293, sequence contact 112 (2 to 3), sequence contact 103 (4) and lamp L^5 to ground. Similarly a circuit for lamp L^6 extends from the live pole of battery 292 through sequence contact 130

70 (14 to 15), conductor 294, sequence contact 113 (3), sequence contact 119 (3) and lamp L^6 to ground. A similar circuit for lamp L^7 extends from the live pole of battery 292 through sequence contact 70 (14 to 15), conductor 295, sequence contact 128 (9) and lamp L^7 to ground. A circuit for lamp L^8 extends from the live pole of battery 296 through sequence contact 71 (14 to 15), conductor 297, sequence contact 137 (5) and lamp L^8 to ground. A similar circuit for lamp L^9 extends from the live pole of battery 296 through sequence contact 71 (14 to 15), conductor 298, sequence contact 145 (1) and lamp L^9 to ground. A like circuit for lamp L^{11} extends from the live pole of battery 296 through sequence contact 71 (14 to 15), conductor 299, sequence contact 146 (0 to 4) and lamp L^{11} to ground. As sequence switch SS' moves from position 13 into position 15, a complete talking circuit between the tandem operator's telephone set TO and the terminating operator's telephone set TO' is completed at sequence contacts 76 (14 to 15) and 77 (14 to 15).

At the time sequence switch SS' moves into position 15, a circuit is also closed for magnet 300 (Fig. 2), which may be traced from the live pole of battery 301 through sequence contact 49 (4 to 5), the winding of relay 300, sequence contact 51 (4 to 17), sequence contact 51 (3 to 5), conductor 200, bank contact 199, wiper 198, sequence contact 64 (3 to 15), sequence contact 64 (14 to 15) and normal contact 190 to ground. The energization of relay 300 by closing alternate contact 302 completes a new circuit for control relay CR which may be traced from the live pole of battery 303 through sequence contact 52 (4 to 9), alternate contact 302, sequence contact 50 (4 to 17), the winding of relay CR, and sequence contact 46 (4 to 17) to ground. As a result of the energization of relay CR, sequence switch SS moves from position 4 to position 6. The circuit for bringing about this result may be traced from the live pole of battery 177 through the winding of magnet SM, sequence contact 56 (4) and alternate contact 178 of relay CR to ground. Immediately following this advance a new starting circuit is provided for the same switch and it is advanced from position 6 to position 7. The starting circuit for bringing about this latter advance extends from the live pole of battery 177 through the winding of magnet SM, sequence contact 56 (6) and normal contact 304 of relay 305 to ground.

With the parts in this condition, the operator having control of the plug P^2 , and having the head-set TO, reads off the number of the called line as the same is indicated by the lamps of Fig. 6, and the distant operator having control of the plug P^3 and having the head-set TO' , upon obtaining

the order, assigns a trunk L^3 , in the usual way, and the operators plug in, the one into jack J^2 of the assigned trunk, and the other into jack J^3 of the called line.

As soon as plug P^2 is inserted into jack J^2 , relay 305 is energized by the closing of a local circuit, which may be traced from the live pole of battery 306 through the winding of relay 305, conductor 307, local contacts of the plug P^2 and jack J^2 and resistance 308 to ground. As soon as relay 305 is energized, a starting circuit is established for sequence switch SS which may be traced from the live pole of battery 177 through the winding of magnet SM, sequence contact 56 (7) and alternate contact 304 to ground. The closing of this circuit causes sequence switch SS to advance from position 7 to position 17.

As a result of this advance of switch SS to position 17, the ground upon conductor 195 is removed by the opening of sequence contact 57 (4 to 8). The removal of this ground opens the previously traced circuit through the right-hand winding of the double wound relay 282, but said circuit is replaced by another which extends through sequence contact 52 (9 to 17), alternate contact 302 of relay 300, sequence contact 50 (4 to 17), the winding of relay CR and sequence contact 46 (4 to 17) to ground. The removal of the ground from conductor 195 also deenergizes relay AR and the test relay TR' of the allotter, which has remained in circuit up to this time and kept the switch SS^2 in connection with the particular finder switch circuit in use. Thus, it will be seen that the allotter stays in engagement with the switch circuit during the time that the lamps are illuminated, and until the tandem operator plugs into the trunk after reading the indication of the lamps to the terminating operator. The allotter is then free to seize a new finder switch circuit which is in the proper condition. In this way, the calls coming in upon the different switch circuits cannot interfere with each other, and only one indication at a time can be set up upon the annunciator lamps.

It will be noted that relay CR is now maintained energized over a local circuit which also includes the right-hand winding of relay 282 and alternate contact 302 of relay 300. The relay 300, although initially energized by a circuit extending through the finder switch S^2 , is now maintained energized by a circuit which may be traced from the live pole of battery 309, through sequence contact 44 (5 to 17), closed contact 283, sequence contact 49 (5 to 17), the winding of relay 300, sequence contact 51 (4 to 17), sequence contact 51 (5 to 17), and alternate contact 178 of relay CR to ground. The circuit for magnet 278 is also somewhat changed by the advance of sequence switch SS to posi-

tion 17. Instead of the circuit extending from battery 279 through sequence contact 45 (4 to 5) directly to the winding of relay 278, it now extends via sequence contact 45 (5 to 17), closed contact 201 of relay CR, sequence contact 43 (5 to 17), sequence contact 43 (5 to 17), to the winding of relay 278. As soon as switch SS advances to position 17, a circuit is established over the sleeve side of the link circuits L^1 and L^2 , which may be traced from the live pole of battery 163, through repeating coil winding 310, the sleeve strand of link circuit L^2 , including engaged contacts 277 and 167, sleeve contacts of switch S, sleeve strand of link circuit L^2 , including sequence contacts 48 (8 to 17) and 48 (8 to 17), conductor 311, closed contact 312 of relay 300, retardation coil 313, closed contact 314 of relay 315, and sequence contact 60 (17) to ground. Of course this circuit will not be established when relay 315 is energized, as will be the case when the circuit is extended to the called line L^4 , but at a time prior to the response of the called party at station N. It may be pointed out at this time that while switch SS is in positions 6 and 7, the previously traced circuit for relay 300 divides at sequence contact 51 (4 to 17) and one branch extends through alternate contact 178 of relay CR, as before traced, and the other branch extends through sequence contact 51 (6 to 7), lamp 316, and relay 317 to ground. The lighting of the lamp 316 indicates when the circuit is in condition for the operator to insert plug P^2 into jack J^2 and the lamp remains lighted until the plug has been so inserted. Relay 317, by means of its contact 318, may extend this signal to any desired distant point for the purpose of supervising the work of the operators.

As before pointed out, the removal of ground from conductor 195, by reason of the advance of sequence switch SS to position 17, caused relay AR to be deenergized. In consequence of such deenergization, sequence switch SS' advances from position 15 to position 16. The circuit by which this advance takes place extends from the live pole of battery 183 through the winding of magnet SM' , sequence contact 67 (15) and normal contact 182 to ground. In consequence of this advance of switch SS' the finder switch S^2 is restored to normal position. This is brought about by the closing of a circuit for restoring magnet RM of said switch. This circuit extends from the live pole of battery 184 through the winding of magnet RM, conductor 319, and sequence contact 81 (16) to ground. The resulting energization of magnet RM withdraws the pawl 194, and forces the lower end of the shaft 10 of switch S^2 into frictional engagement with the constantly driven disk 12, and as a result, the switch is drawn down into its normal posi-

tion. As soon as the finder switch S^2 gets back to its normal position, its grounded contact brush 320 engages commutator contact 321, and thereby completes a starting circuit for sequence switch SS' by which it is moved from position 16 to position 17. The entire circuit may be traced from ground at contact brush 320, through said brush, contact 321, conductor 322, sequence contact 67 (3 to 16) and winding of magnet SM' to battery 183. The advance of switch SS' from position 15 to position 16 opens the connections from batteries 292 and 296 to the various lamps of the annunciator. Likewise, as before indicated, the test circuit of the allotter test relay TR' is interrupted at sequence contact 72 (13 to 15) by the same movement of sequence switch SS'. In positions 16 and 17 of switch SS', a releasing circuit is established for sequence switch SS⁴ which may be traced from the live pole of battery 202, through the winding of magnet SM^4 , sequence contact 91 (0 to 15), conductor 323 and sequence contact 75 (16 to 17) to ground. As a result of the closing of this circuit, sequence switch SS⁴ advances to position 16. As soon as switch SS⁴ reaches position 16, a circuit is established for advancing the brush selecting shaft 30 to its normal position. This circuit extends from the live pole of battery 231, through the winding of magnet 33, conductor 324, normal contact 325 of relay 326, and sequence contact 97 (16) to ground. This circuit will be maintained until relay 326 is energized. The circuit for energizing said relay extends from the live pole of battery 327, through sequence contact 100 (15 to 16), the winding of relay 326 and closed off-normal contacts 238 and 239 to ground. It will be remembered that these contacts are brought into engagement when the shaft 30 reaches its normal position. As soon as relay 326 is energized, a new release circuit will be established, this time for the brush advancing magnet 17. This circuit may be traced from the live pole of battery 245, through the winding of magnet 17, conductors 246 and 328, normal contact 329 of relay 330, alternate contact 325 of relay 326, and sequence contact 97 (16) to ground. This circuit will continue until interrupted at contact 329 by the energization of relay 330. The circuit for bringing about such energization extends from the live pole of battery 327, through sequence contact 100 (15 to 16), the winding of relay 330 and closed off-normal contacts 255 and 256 to ground. These off-normal contacts are brought into engagement when the switch wipers reach their normal position. It will be noted that as soon as sequence switch SS⁴ reached position 16, so as to close sequence contact 100 (15 to 16), similar circuits were at once established for relays 331 and 332, through the correspond-

ing off-normal contacts 238^a and 239^a, in the one case, and 255^a and 256^a in the other case. The result of such energization is the closing of alternate contacts 333 and 334 of said relays. Upon the closing of said alternate contacts, sequence switch SS⁴ is advanced from position 16 to its normal position. The circuit by which such advance is brought about extends from the live pole of battery 10 202, through the winding of magnet SM⁴, conductor 335, alternate contacts 334, 333, 329 and 325, and sequence contact 97 (16) to ground. As soon as the switch SS⁴ advances to normal, the circuit just traced is opened 15 at sequence contact 97 (16), and the circuits of relays 326, 330, 331 and 332 are opened at sequence contact 100 (15 to 16). The opening of off-normal contacts 239 and 240 and of 256 and 257, brings about the de- 20 energization of relays 214 and 217. Thus, the switches SS⁴ and S³ and their associated parts are restored to normal.

As a result of advancing sequence switch SS' to position 17, circuits are completed for 25 the restoration of the sequence switches SS⁵, SS⁶, SS⁷, SS⁸, SS⁹ and SS¹⁰. The restoring circuit for switch SS⁵ extends from the live pole of battery 260 through the winding of magnet SM⁵, sequence contact 107 (0 to 16), conductor 336, sequence contact 79 (16 to 17), conductor 220, and normal contact 182 to ground. The restoring circuit for sequence switch SS⁶ extends from the live pole of battery 262, through the winding of magnet SM⁶, sequence contact 114 (0 to 16), conductor 337 and sequence contact 79 (16 to 17), conductor 220 and normal contact 182 to ground. The restoring circuit for sequence switch SS⁷ extends from the live 40 pole of battery 264, through the winding of magnet SM⁷, sequence contact 123 (0 to 16), conductor 339 and sequence contact 80 (16 to 17) to ground. It may be pointed out that signal lamp 338 is provided in association with sequence contact 80 (13 to 14) to indicate the presence of sequence switch SS' in these positions. Since said switch passes from position 13 to position 15 by one advance movement, this lamp 338, therefore, 45 is lighted practically only while the switch SS' is in position 13. The restoring circuit for sequence switch SS⁸ extends from the live pole of battery 266, through the winding of magnet SM⁸, sequence contact 131 (0 to 16), conductor 340 and sequence contact 80 (16 to 17) to ground. The restoring circuit for sequence switch SS⁹ extends from the live pole of battery 268, through the winding of magnet SM⁹, sequence contact 139 (0 to 16), conductor 341 and sequence contact 81 (16 to 17) to ground. The restoring circuit for sequence switch SS¹⁰ extends from the live pole of battery 270, through the winding of magnet SM¹⁰, sequence contact 65 147 (0 to 16), conductor 342 and sequence

contact 81 (16 to 17) to ground. In each of these several sequence switches, the restoring circuit is maintained until the switch reaches its normal position. When this position is reached the circuit is interrupted 70 at the adjacent sequence contact.

The restoration of the sequence switches associated with the annunciator lamps establishes a starting circuit for sequence switch SS', by which it is moved from position 17 75 to position 18. This circuit may be traced from the live pole of battery 183, through the winding of magnet SM', sequence contact 67 (17), conductor 343, sequence contact 92 (N), conductor 212, normal contact 213, conductor 215, normal contact 216, conductor 218, sequence contacts 108 (N), 115 (N), 124 (N), 132 (N), 140 (N), 148 (N), conductor 219, sequence contact 79 (17), conductor 220 and normal contact 182 to 85 ground.

The sequence switch SS' remains in position 18 awaiting allotment by the sequence switch SS³. The function of this allotting switch is to bring the circuits of the finder 90 switches S² into starting condition, one by one, and thus prevent the starting of a plurality of finder switches in response to the same call. At the conclusion of its operations, each finder circuit is left with its sequence switch SS' in position 18. The allotter switch SS³ is arranged to pick out one such circuit, and advance its switch SS' into position 1, the starting position. Then the allotter switch SS³ advances to another 100 finder switch circuit, and in like manner advances it, but only after the first circuit has been brought into service. In the particular circuits illustrated, the switch SS³ seizes a finder switch circuit whose switch SS' is 105 in position 18 and remains in circuit with it until it has advanced through positions 1, 2 and 3 and into position 4. Then the allotter switch SS³ finds another circuit whose sequence switch SS' is in position 18, and 110 the operation is repeated.

With the switch SS' in position 18, a starting circuit for its magnet SM' extends through sequence contact 69 (18 to 3), sequence contact 69 (4 to 18) and sequence contact 88 (1) to ground. This starting circuit causes switch SS' to move into position 1, its starting position. When in the operation of the parts the switch SS' is moved into position 4, as heretofore described, the allotter switch SS³ advances, by reason of a circuit which may be traced from the live pole of battery 344, through the winding of magnet SM³, conductor 345, sequence contact 69 (4 to 17), sequence contact 69 (4 to 18), conductor 346 and sequence contact 88 (1) to ground. Switch SS³ will then advance until its magnet SM³ 120 cannot find a circuit corresponding to that just traced through branch conductor 346. 130

This break will occur whenever a circuit is met whose switch SS' is in position 18. At such time the circuit will be interrupted at sequence contact 69 (4 to 17).

- 5 Upon the insertion of plug P² into jack J², a circuit is established through the windings of magnet 347 and relay 315, the former being at the distant exchange and the latter at the exchange of the tandem operator. This circuit may be traced from the live pole of battery 348, through the upper winding of magnet 347, normal contact 349 of relay 350, conductor 351, repeating coil winding 352, tip strand of link circuit L³, 10 jack and plug tip contacts, sleeve strand of link circuit L², including sequence contact 57 (9 to 17) and sequence contact 57 (9 to 17), the winding of relay 315, closed contact 353 of relay 282, the sleeve strand of 15 link circuit L², plug and jack sleeve contacts, the sleeve strand of link circuit L³, repeating coil winding 354, conductor 355, normal contact 356 of relay 350, and the lower winding of magnet 347 to ground. The result of closing this circuit is to energize 20 magnet 347 and relay 315. Before the distant operator, the energization of magnet 347 may be utilized to display a signal or otherwise indicate to her that plug P², under the control of the tandem operator, has 25 been inserted into jack J². As soon as the plug P³ controlled by the terminating operator is inserted into jack J², current flows from battery 357, through coil 358, plug and 30 jack local contacts, and the winding of cut-off relay CO' to ground. The energization of the latter relay opens its contacts 157^a and 158^a, and thereby cuts off the relay LR', so as to prevent a flow of current from battery 156^a and a possible closing of the 35 circuit of lamp LL' from battery 160^a, through relay contact 159^a to ground. The terminating operator next depresses her ringing key 40 359 and applies ringing current to actuate the call bell of the substation N. As soon as the called party responds by removing his receiver from its hook, a circuit is completed over the tip and sleeve sides of the link circuit L³ and line L⁴, which may be traced 45 from the live pole of battery 360, through repeating coil winding 361, the winding of relay 362, ringing key sleeve contacts, plug and jack sleeve contacts, out over the line through the substation and back through 50 55 jack and plug tip contacts and repeating coil winding 363 to ground. The closing of this latter circuit supplies transmission current to the substation N and at the same time energizes relay 362. The energization of relay 362 completes a local circuit for relay 350, which may be traced from the live pole of battery 364, through the winding of relay 350, and closed contact 365 of relay 362 to ground. The energization of relay 350 55 opens the circuit through the windings of

magnet 247 and relay 315, but a substituted circuit maintains the magnet 347 energized. This circuit extends from the live pole of battery 348, through the upper winding of magnet 347, conductor 366, alternate contact 356 and the lower winding of magnet 347 to ground. The deenergization of relay 315 restores the branch to ground through the retardation coil 313, and thereby provides a flow of current from battery 163, 70 over the sleeve side of the circuit through said retardation coil 313. At the same time, current is supplied from battery 279, over the tip side of the circuit, to ground at 281. A suitable coil 367 in the sleeve strand of 75 link circuit L³ and the magnet 347 are located before the initiating and terminating operators, and may be used for supervisory purposes. In the case of the terminating operator, the magnet 358 may also be used for 80 this purpose. The magnets 347 and 358 may be used either alone or in combination, as desired. The tip and sleeve strands of the link circuit L², which constitute a portion of the talking circuit, are provided with interposed condensers 368 and 369. Likewise, the 85 left-hand portion of the link circuit L³, which is that portion which extends between the tandem operator's station and the distant terminating operator's station, is also 90 provided with a condenser 370 which is interposed between the repeating coil windings 352 and 354. The heavily marked circuit of Figs. 1, 2 and 3 represents the talking circuit 95 established between substations M and N. 100

At the conclusion of conversation, the parties at substations M and N restore their receivers to their switchhooks. The restoration of the receiver at substation M deenergizes the magnet 367, and the initiating operator in response thereto, withdraws the plug P from jack J. Upon doing so, the circuit of the line L and its associated parts return to their normal condition. The associated selector switch S is also returned to normal by any suitable mechanism, or, as far as the present disclosure is concerned, it may be restored by hand. As soon as switch S is restored and the link circuits L¹ and L² disconnected, relay 278, which is connected to the tip side of the circuit is deenergized. The deenergization of relay 278 opens the maintaining circuit of relay 300 at contact 283, and the relay 300 is deenergized, with a consequent opening of the circuit of control relay CR at contact 302. As soon as relay CR is deenergized, sequence switch SS is advanced from position 17 to position 1, its initial position. The circuit by which this is accomplished extends from battery 177, through the winding of magnet SM, sequence contact 56 (6 to 17) and normal contact 178 to ground. The deenergization of relay 300 also opens the maintaining circuit 125 130

of relay 282, and the latter opens contact 353 and prevents the further energization of relay 315.

When the tandem operator withdraws plug P^2 from jack J^2 in response to the changed condition of supervisory magnet 313, the local circuit through relay 305 is interrupted and the latter is deenergized.

When the terminating operator removes plug P^3 from jack J^3 in response to the changed condition of the supervisory apparatus, the local circuit through magnet 358 and cut-off relay CO' is broken, and the circuit of the line L^4 and its associated parts are restored to their normal condition. At the same time relay 362 is deenergized, with the result that magnet 347 has its maintaining circuit interrupted at alternate contact 356, and although its windings are connected to opposite strands of the link circuit L^3 , there can be no circuit over the trunk wires to the tandem operator's position because of the previous withdrawal of plug P^2 from jack J^2 . Thus, the apparatus of the terminating operator's position is also restored to normal.

If the terminating operator had removed plug P^3 before the tandem operator had removed plug P^2 , then upon the deenergization of relay 362, electromagnet 347 would be maintained energized over the trunk circuit, through the winding of relay 315, and the latter relay would be energized again. No matter in what order the plugs are withdrawn from their jacks, the parts of the circuits are all restored to their normal condition.

Attention may be called at this point to the employment of a signal lamp 384, in association with the contacts 53 and 54 of sequence switch SS and flashing interrupter 55. Batteries 385 and 386 are associated with the contact 53, and the flashing interrupter 55, respectively, and, in the proper positions of the associated contacts, these batteries supply current to the lamp 384 by way of contact 54 and the ground connection to contact 304 of relay 305. For example, the lamp 384 is lighted when switch S is restored to its normal position, and sequence switch SS moves from position 17 into position 1. The circuit will be from battery 385, sequence switch contact 53 (18 to 6), lamp 384, sequence switch contact 54 (1 to 6, 8 to 18), sequence switch contact 54 (18 to 6), alternate contact 304 of relay 305 to ground. The lamp will light and burn steadily over this circuit, and will indicate to the tandem operator that the initiating operator has taken down the connection. Had it happened that the tandem operator had withdrawn plug P^2 before the initiating operator had disconnected, this would have released the relay 305, and since sequence switch SS is still in position 17, a circuit

would have been completed from battery 386, through flashing interrupter 55, lamp 384, sequence switch contact 54 (1 to 6, 8 to 18), sequence switch contact 54 (8 to 17) and normal contact 304 to ground, and the flashing of the lamp over this circuit would have indicated to the tandem operator the condition of the circuits at the initiating office.

The substation sets may be of any desired construction and arrangement. In the present instance, at each substation there is a transmitter 371, hook switch 372, receiver 373, condenser 374, induction coil 375 and call bell 376. Likewise, the telephone operators' sets may be of any preferred construction. In each of the instances illustrated, the set includes a transmitter 377, impedance coil 378, battery 379, condenser 380, repeating coil 381, resistance 382 and head receiver 383. It may be noted that beside the test jack J^4 (Fig. 4) I have provided test jacks J^5 and J^6 . In association with the jack J^4 I have indicated test plug P^4 . The illustration of this test plug and these test jacks, however, is merely incidental as they are not essential to the understanding of the circuit or to its operation. Throughout the diagram connections from a common conductor to a plurality of branches are indicated by a tuft of lines running from the common conductor.

In carrying out my invention, it is obvious that many changes and alterations may be made in the details of the circuits and apparatus employed, without departing from its spirit and scope. I therefore do not wish to be unduly limited in this regard, but aim to cover all such alterations and modifications by the terms of the appended claims.

What is claimed is:

1. In a telephone system, telephone lines, link circuits including automatic switches for extending said telephone lines, operators' telephone sets, automatic switch controlling mechanism, order wires, and other automatic switches for interconnecting said operators' telephone sets through said order wires, said other automatic switches being responsive to said controlling mechanism when operated in controlling said link circuits.

2. In a telephone system, telephone lines, link circuits including automatic switches for extending said telephone lines, operators' telephone sets, automatic switch controlling mechanism, order wires, other automatic switches for interconnecting said operators' telephone sets through said order wires, said other automatic switches being responsive to said controlling mechanism when operated in controlling said link circuits, and means for independently restoring said other automatic switches.

3. In a telephone system, a first class of operators' positions each including an auto-

- matic switch controlling mechanism, a second class of operators' positions each including a number indicating device and an operator's set, a third class of operators' positions each including an operator's set, order wires including automatic switches for interconnecting the operators' sets of said second and third classes of positions, telephone lines, and means under the control of operators at said first class of positions for extending said lines to said positions of the second class for simultaneously setting said number indicating devices and also for simultaneously controlling said order wire automatic switches. 4. In a telephone system, a first class of operators' positions each including an automatic switch controlling mechanism, a second class of operators' positions each including a number indicating device and an operator's set, a third class of operators' positions each including an operator's set, order wires including automatic switches for interconnecting the operators' sets of said second and third classes of positions, telephone lines, means under the control of operators at said first class of positions for extending said lines to said positions of the second class, for simultaneously setting said number indicating devices and also for simultaneously controlling said order wire automatic switches, and means under the control of operators at said third class of positions for disestablishing order wire circuits thus set up. 5. In a telephone system, telephone lines, means including automatic switches for extending said lines, operator controlled link circuits for further extending said lines, operators' positions including automatic switch controlling mechanism for controlling said switches, operators' positions located at either end of said link circuits each including an operator's set, and order wires including automatic switches for interconnecting said link circuit operators' sets, said order wire switches being also under control of said mechanism. 6. A telephone system comprising a sending mechanism, a plurality of link circuits, a switch for connecting said mechanism to said link circuits individually, a finder switch for picking out a link circuit to which said mechanism has been connected, an annunciator at an operator's station, switch mechanism responsive to the setting of said sending mechanism to display an indication thereon corresponding to the particular setting of said sender mechanism, an operator's set at said station, distant operators' stations, other operators' sets at said distant stations, order wire trunks extending from said first operator's station to said distant stations, automatic switches responsive to the setting of said sending mechanism to connect said first operator's set to trunks extending to a distant station and to the operator's set at said station in accordance with the particular setting on said sending mechanism, and means under the control of said first and selected distant operator for extending the circuit of the link circuit to which said sending mechanism has been connected. 7. A telephone system including a sending device, an annunciator at an operator's station, automatic switches, order wires extending therefrom to distant operators' stations, operators' sets at all of said stations, means for connecting said sending device into circuit with said annunciator and automatic switches, means responsive to the setting of said sending device to cause said switches to connect the first operator's set in circuit over a selected order wire with the operator's set at a predetermined distant station and to display on said annunciator an order for the first operator to give the distant operator over the connected order wire circuit. 8. In a telephone system, telephone lines, operators' positions, order wires including automatic switches for interconnecting said operators' positions, means under control of an operator at one position for extending a line to a second operator's position, and for simultaneously controlling said switches to interconnect said second operator's position with a third operator's position, and means under control of the operator at said third position for disestablishing the connection between said second operator's position and said third operator's position. 9. A telephone system including a link circuit, a plurality of other link circuits, a first operator's equipment for uniting said first link circuit to any one of said other link circuits, distant operators' equipments for extending the circuits of said other link circuits at said distant operators' positions, a sender associated with said first link circuit, order wires, automatic switch mechanism responsive to the condition of said sender to connect said order wires into an order circuit between said first operator's equipment and that of one of a predetermined group of said distant operators, and means responsive to an act of said first operator to free said order wire conductors and said switch mechanism for further service. 10. A telephone system including a link circuit, a plurality of other link circuits, a first operator's equipment for uniting said first link circuit to any one of said other link circuits, distant operators' equipments for extending the circuits of said other link circuits at said distant operators' positions, a sender associated with said first link circuit, order wire conductors, automatic switch mechanism responsive to the setting

- of said sender to connect said order wires into an order circuit between said first operator's equipment and that of a predetermined one of said distant operators, and 5 means responsive to the uniting of said first link circuit to any one of said other link circuits to free said order wires and automatic switch mechanism for use in connection with the extension of other circuits.
- 10 11. A telephone system comprising an operator's set, an automatic switch individual to said set, conductors for connecting said set to said switch, trunks leading from said switch, other operators' sets associated with 15 the distant ends of said trunks respectively, sending mechanism, circuits wholly independent of said conductors and responsive to said sending mechanism for controlling said switch, and main talking conductors 20 and associated means also responsive to said sending mechanism for establishing a main talking circuit exclusive of said automatic switch, said connecting conductors and said trunks.
- 25 12. A telephone system comprising an operator's set, an automatic switch individual to said set, conductors for connecting said set to said switch, trunks leading from said switch, other operators' sets associated with 30 the distant ends of said trunks respectively; sending mechanism, circuits wholly independent of said conductors for controlling said switch; main talking conductors and associated means for establishing a main 35 talking circuit exclusive of said automatic switch, said connecting conductors and said trunks, and means responsive to the connection of main talking conductors together, to free said automatic switch, connecting conductors and trunks for further service.
- 40 13. A telephone system including a plurality of switches each having coöperating wipers and bank contacts, a plurality of groups of trunks leading from each of said 45 switches, a set of conductors, sending mechanism, means responsive to the condition of the sending mechanism to connect said conductors to the wipers of a particular switch, means further responsive to said sending 50 mechanism for causing the wipers of said particular switch to engage only the bank contacts of a particular group of trunks, and means for transmitting an order to an operator over conductors and trunks thus connected, and main talking conductors and associated 55 means partly under the control of said operator and partially under control of said sending mechanism for establishing a main talking circuit exclusive of said conductors and trunks.
- 60 14. A telephone system including a plurality of switches each having coöperating wipers and bank contacts, a plurality of groups of trunks leading from each of said 65 switches, a set of conductors, sending mech-
- anism, means responsive to the condition of the sending mechanism to connect said conductors to the wipers of a particular switch, means further responsive to said sending mechanism for causing the wipers of said particular switch to engage only the bank contacts of a particular group of trunks, 70 means for transmitting an order to an operator over conductors and trunks thus connected, main talking conductors and associated means partly under the control of said operator for establishing a main talking circuit exclusive of said conductors and trunks, and means whereby said operator upon exercising her control in 75
15. A telephone system including a plurality of switches each having coöperating 80 wipers and bank contacts, a plurality of groups of trunks leading from each of said switches, a set of conductors, sending mechanism, means responsive to the condition of the sending mechanism to connect said 85 conductors to the wipers of a particular switch, means further responsive to said sending mechanism for causing the wipers of said particular switch to engage only the bank contacts of a particular group of trunks, control circuits responsive to said sending mechanism wholly independent of said trunks and conductors for controlling said connecting means and said causing means, means for transmitting an order to an operator over 90 conductors and trunks thus connected, and main talking conductors and associated means partly under the control of said operator and partially under control of said sending mechanism for establishing a main 95 talking circuit exclusive of said control circuits, conductors and trunks.
- 100 16. A telephone system including a plurality of switches each having coöperating wipers and bank contacts, a plurality of groups of trunks leading from each of said switches, a set of conductors, sending mechanism, means responsive to the condition of the sending mechanism to connect said conductors to the wipers of a particular switch, 105 means further responsive to said sending mechanism for causing the wipers of said particular switch to engage only the bank contacts of a particular group of trunks, control circuits wholly independent of said 110 trunks and conductors for controlling said connecting means and said causing means, means for transmitting an order to an operator over conductors and trunks thus connected, main talking conductors and associated 115 means partly under the control of said operator for establishing a main talking circuit exclusive of said control circuits, conductors and trunks, and means whereby said operator upon exercising her control in 120
- 125
- 130

the formation of said main talking circuit frees said automatic switch, conductors and trunks for further service.

17. A telephone system comprising a sending mechanism, a plurality of link circuits, a switch for connecting said mechanism to said link circuits individually, a finder switch for picking out a link circuit to which said mechanism has been connected, 5 an annunciator at an operator's station, switch mechanism responsive to the setting of said sending mechanism to display an indication on said annunciator corresponding to the particular setting of said sender 10 mechanism, an operator's set at said station, distant operators' stations, other operators' sets at said distant stations, order wire trunks extending from said first operator's station to said distant stations, automatic 15 switches responsive to the setting of said sending mechanism to connect said first operator's set to trunks extending to a distant station and to the operator's set at said station in accordance with the particular 20 setting on said sending mechanism, means under the control of said first and selected distant operator for extending the circuit of the link circuit to which said sending mechanism has been connected, and means 25 responsive to said first operator's extension of said circuit to free said finder switch, annunciator, switch mechanism, operators' sets, trunks and automatic switches for further 30 service.
35. 18. A telephone system including a sending device, an annunciator at an operator's station, automatic switches, order wires extending therefrom to distant operators' stations, operators' sets at all of said stations, 40 means for connecting said sending device into circuit with said annunciator and automatic switches, means responsive to the setting of said sending device to cause said switches to connect the first operator's set in 45 circuit over a selected order wire with the operator's set at a predetermined distant station and to display on said annunciator an order for the first operator to give the distant operator over the connected order wire 50 circuit, and main talking conductors and associated means for establishing a main talking circuit exclusive of said automatic switches and order wires.
55. 19. A telephone system including a sending device, an annunciator at an operator's station, automatic switches, order wires extending therefrom to distant operators' stations, operators' sets at all of said stations, means for connecting said sending device 60 into circuit with said annunciator and auto-
- matic switches, means responsive to the setting of said sending device to cause said switches to connect the first operator's set in circuit over a selected order wire with the operator's set at a predetermined distant 65 station and to display on said annunciator an order for the first operator to give the distant operator over the connected order wire circuit, main talking conductors and associated means for establishing a main 70 talking circuit exclusive of said automatic switches and order wires, and means responsive to the connection of main talking conductors together to free said automatic switches and order wires used in bringing 75 about that particular main talking circuit.
20. A telephone system including conductors available for establishing a plurality of talking circuits, order wires, operators' sets, an annunciator, a sender, automatic switch mechanism for operating in response to the control of said sender to display an order on 80 said annunciator and connect operators' sets over said order wires, and means for associating said operators' sets, annunciator and 85 automatic switch mechanism with the conductors of a second talking circuit while said first talking circuit is still in use.
21. A telephone system comprising telephone lines, link circuits including automatic switches for extending the circuit of a calling line, link circuits under the control of two operators for further extending the circuit of a calling line, operators' telephone sets for each of said operators, order 90 wires for connecting said sets, a sender for controlling said automatic switches, switching mechanism responsive to said sender to establish a portion of the order wire circuit between said sets, and an allotting switch for 95 causing said switching mechanism to complete said order wire circuit.
22. A telephone system comprising telephone lines, link circuits under the control of two operators for extending the circuit of a 105 calling line, operators' telephone sets for each of said operators, order wires for connecting said sets, a sender, a set of annunciator signals, circuits for said signals, switching mechanism responsive to said sender to 110 establish a portion of the order wire circuit and to establish a portion of the circuits for said signals, and an allotting switch for causing said switching mechanism to complete said order wire circuit and to complete the 115 circuits for said signals.

In witness whereof, I hereunto subscribe my name this 25th day of August A. D. 1916.

ALBEN E. LUNDELL.
